UNITED STATES PATENT OFFICE

152,703

DESIGN FOR A BUILDING

Joseph A. King, Whitman, Mass.

Application October 1, 1947, Serial No. 141,704

Term of patent 14 years

(Cl. D13—1)

To all whom it may concern:

Be it known that I, Joseph A. King, a citizen of the United States, residing at Whitman, in the county of Plymouth and State of Massachusetts, have invented a new, original, and ornamental Design for a Building, of which the following is a specification, reference being had to the accompanying drawing, forming part thereof.

Figure 1 is a perspective view of a building, showing my new design, and

Figure 2 is a top plan view thereof.

The appearance of the undisclosed portion of the building is substantially similar to the side disclosed by Figure 1 except for the omission of the draw bridge doorway.

I claim:

The ornamental design for a building, as shown and described.

JOSEPH A. KING.
